(57) **CLAIM**

The ornamental design for a reflective light housing, as shown and described.

DESCRIPTION

FIG. 1 is a perspective view of the reflective light housing, and according to the new and unique design;

FIG. 2 is a top view of the reflective light housing of FIG. 1;

FIG. 3 is a right side view in elevation of the reflective light housing of FIG. 1;

FIG. 4 is a front side view in elevation of the reflective light housing of FIG. 1;

FIG. 5 is a rear side view in elevation of the reflective light housing of FIG. 1; and,

FIG. 6 is a bottom view of the reflective light housing of FIG. 1.

The broken line showing of the inner element is included for the purpose of illustrating only and forms no part of the claimed design.
